BLIND STITCH SEWING MACHINE

Samuel Boigon, Toronto, Ontario, Canada

Application October 20, 1937, Serial No. 170,064

4 Claims. (Cl. 112—176)

This invention relates to a blind stitch sewing machine.

The objects of the invention, generally, are to improve on known blind stitch sewing machines.

5 A specific object of the invention is to provide such a machine capable of forming and stitching a seam in a piece of fabric so that the stitching does not show on one face or side of the fabric.

Another specific object of the invention is to 10 provide means for so holding the fabric as it is fed to the needle, that the fabric will be firmly held in folded position when presented to the action of the needle and while being acted upon by the needle.

15 In the drawings, wherein like numerals of reference indicate corresponding parts in the various figures,

Figure 1 is a side elevation of a blind stitch sewing machine provided with my improvements, 20 the work table being shown in dotted lines only;

Figure 2 is a fragmentary, perspective view of Figure 1, but showing the work table;

Figure 2A is a view similar to Figure 2, but without the work table;

25 Figure 3 is a more or less diagrammatic view of a fragment of fabric, illustrating the stitching made by my present improved machine;

Figure 4 is a top plan view of the member upon which the fabric slides when being fed to the 30 needle;

Figure 5 is a side elevation of Figure 4;

Figure 6 is a fragmentary top plan view of Figure 2A;

Figure 7 is a detail of construction, showing 35 more particularly the member co-operating with the member shown in Figures 4 and 5.

The present invention is illustrated herein as embodied in a blind stitch sewing machine of a well-known type, as manufactured by United 40 States Blind Stitch Machine Corporation, more particularly a machine sold as model B-88.

Such a machine includes a stitch forming mechanism and a work presenting mechanism which co-operate to form a line of single thread 45 chain stitches and anchor said stitches in the opposite inner faces of a piece of fabric. The space between the stitching may be folded so as to form, say, a pressed seam.

The invention is thus particularly useful in 50 imparting a permanent crease to a trouser leg. A piece of fabric, which is to be made into a trouser leg, is placed upside down and fed lengthwise through the machine, so that the stitches enter and emerge from the inner side only of the 55 fabric and are, therefore, not exposed on the outer

face thereof, that is, on the outside of the trouser leg.

The stitching accomplished by such a machine is diagrammatically illustrated in Figure 3 of the drawings. For instance, the line of stitches includes a series of connected and uniformly spaced anchored needle loops *b*. Each loop *b* enters the inner face of the fabric and emerges from said face on each side of a fold *F*. Each loop *b* includes two portions, *p* and *p1*, which extend twice 10 across the fold, and are disposed at an angle to each other, the portion *p* extending at right angles to the fold and the portion *p1* extending at a substantial angle thereto. The degree of inclination depends on the length of the stitch, or, 15 in other words, on the distance between points of needle penetrations. The portion *p1* is the closed end of the loop, and this loop is anchored by the next formed needle thread loop. The needle thread loops *b* enter and emerge on one 20 side of the fold along lines which are fairly close to the fold, and are spaced equidistant therefrom, thus not only maintaining the fold, but also maintaining the fold in a uniform manner 25 throughout its length.

The machine includes a base or plate *10*, a post or standard *11*, and an overhanging arm *12* supporting at its outer end a presser-foot *13*, a needle arm *14* with curved needle *15*, a looper mechanism *M* of which *16* is the looper proper, and feed 30 mechanism of which *17* is the feed dog. The dog *17* is actuated by means such as is used in said model B-88 to impart to the dog a more or less oval trajectory such as permits of the dog engaging the fabric (not shown) to feed the same 35 to the needle *15*. The needle arm *14* is fixedly mounted on one end of a shaft *18* to which is imparted an oscillatory motion by means such as is used in said model B-88. The presser-foot *13* has an elongated work-receiving opening *19*, and 40 its upper face is formed with needle guides *20* at right angles to the axis of the opening *19*.

Disposed under the presser-foot so as to normally engage its underface is a support or guide *22* over which the fabric or work may slide. The 45 guide turns on a shaft *23* mounted on one end of a lever *24* pivotally mounted on the shaft *25* supported by the work table *W*, the lever having a crank *26* adapted to receive one end of a tensioned spring *27* whose other end is attached to 50 a lug *28* of the work table *W*. The arrangement is such, therefore, that the guide *22* normally engages the underside of the presser plate, and permits of the guide being pressed or moved bodily 55 downwardly under the pressure of the feed dog as

the same is on its rearward or feeding stroke. The guide is best shown in Figures 4 and 5. At its forward end, it is formed to provide a slot 27A, and is formed rearwardly of the slot with 5 a recess 28; this recess accommodates the stitched fold in the fabric as the fold, once formed or stitched, moves rearwardly from the needle.

Disposed within the slot 27A and forwardly of the plane of the path of the needle is a member 10 29 having an upper curved edge recessed or grooved longitudinally as at 31. This member is fixed to the work table as on a non-rotatable shaft 30A. Co-operating with the groove is a resilient or flexible member or rod 32, one end of the rod 15 being fixed to a lug 33 from the presser plate and the other or free end engaging and pressing into the groove or recess 31. The member 29 and co-operating resilient finger 32 form means adapted for imparting two symmetrically formed and 20 symmetrically directed folds to the fabric or work just ahead of the plane of the needle path, the work being thus presented to the action of the needle in two spaced folds. The depth of the recess or groove determines the height of pleat or fold.

It was found that the needle when passing through the spaced folds of a folded fabric had a tendency to at least push one of the folds to one side, that is, away from the point of the needle. 30 Accordingly, to obviate this difficulty, I provide a member 36 having a projecting point or finger 36A which terminates just short of the plane of the path of the needle and lies just to one side of the fold forming member 29. The lower face 35 of the finger at its end normally lies slightly below the upper end of the member 29 which is nearest the needle, so that the finger will operate to prevent the fabric from substantially being pushed or drawn with the needle when the latter is on its stitching stroke. For that purpose, 40 the plate 36, from which the finger 36A extends, is journaled on a shaft 37 fixed at the end of an arm 38, which arm depends from a lug 39 secured to the head of the machine. A spring 40 tensioned between the arm and plate serves to urge 45 the plate toward the presser-foot.

Fixed to the table W aforesaid, is a plate 9 which, in effect, operates as the work table in lieu of the table W. The table W now merely forms a support for the plate or work table 9. Formed into the rear edge of the plate 9 is a slot 20A disposed in alignment with the axis of the 50 resilient member 32. This plate is also so disposed above the table W, that its upper face is slightly above the rod 32 where the same joins the lug 33, all as best suggested in dotted lines in Figure 1. The slot 20A thus co-operates with the rod 32 to 55 initiate the fold in the fabric, which fold is com-

pleted when the fabric lies between the rod and the member 29, just in advance of the path of the needle.

What I claim is:—

1. In a sewing machine for blind stitching, the 5 combination of a presser-foot having an opening, a needle mounted to reciprocate above said opening, a fabric feeding mechanism, a member fixed substantially in the axis of said opening over which the fabric slides when acted upon by said 10 feeding mechanism, said member having a groove, and a resilient member having one portion engaging in said groove and forming with said first member means for imparting two symmetrically formed and symmetrically directed folds to the 15 fabric so as to present two spaced folds into the path of said needle.

2. In a sewing machine for blind stitching, the 20 combination of a presser-foot having an opening, a needle mounted to reciprocate above said opening, a fabric feeding mechanism, a member fixed substantially in the axis of said opening over which the fabric slides when acted upon by said 25 feeding mechanism, said member having a groove, a resilient member having one portion engaging in said groove and forming with said first member means for imparting two symmetrically formed and symmetrically directed folds to the 30 fabric so as to present two spaced folds into the path of said needle, and a spring-pressed finger adapted to engage at substantially its extremity the fabric at a point slightly clear of the needle path and slightly to one side of said first member.

3. In a sewing machine for blind stitching, the 35 combination of a presser-foot having an opening, a needle mounted to reciprocate above said opening, a fabric feeding mechanism, a member fixed substantially in the axis of said opening over which the fabric slides when acted upon by said 40 feeding mechanism, said member having a groove, a resilient member having one portion engaging in said groove and forming with said first member means for imparting two symmetrically formed and symmetrically directed folds to the 45 fabric so as to present two spaced folds into the path of said needle, and a spring-pressed finger adapted to engage at substantially its extremity the fabric at a point slightly clear of the needle path and slightly off the side of said first member 50 which lies nearest the point of the needle when the same is in penetrating position.

4. In a machine as set forth in claim 1, a spring-pressed finger adapted to engage the fabric at a point slightly clear of the needle path and 55 clear of said resilient member.

SAMUEL BOIGON.
